UNITED STATES PATENT OFFICE.

BRAINERD DYER, OF HUDSON, OHIO, ASSIGNOR TO VITREOUS STEEL PRODUCTS COMPANY, OF CLEVELAND, OHIO, A CORPORATION OF OHIO.

DESIGN FOR A TABLE TOP OR ARTICLE OF SIMILAR NATURE.

Application filed December 19, 1927. Serial No. 24,540. Term of patent 14 years.

To all whom it may concern:

Be it known that I, BRAINERD DYER, a citizen of the United States, residing at Hudson, in the county of Summit and State of Ohio, have invented a new, original, and ornamental Design for a Table Top or Article of Similar Nature, of which the following is a specification, reference being had to the accompanying drawing, forming a part thereof.

In the drawing:

Fig. 1 is a plan view of a table top, or article of similar nature showing my new design.

Fig. 2 is a side elevation thereof.

I claim:

The ornamental design for a table top or article of similar nature substantially as shown.

In testimony whereof I affix my signature.

BRAINERD DYER.
